METHOD OF REMOVING VOLATILE ORGANIC MATERIAL

William Alfred Fessler, Camillus, N. Y., assignor
to The Solvay Process Company, New York,
N. Y., a corporation of New York

Application March 13, 1942, Serial No. 434,578

12 Claims.

(Cl. 202—46)

This invention relates to detergent compositions and is particularly concerned with the purification of aqueous solutions of detergents of good foaming qualities.

In the manufacture or manipulation of aqueous detergent solutions it frequently happens that substantial quantities of volatile organic material are introduced into the solutions. Thus, in the purification of detergents derived from hydrocarbon sources it is often desirable to remove unconverted water-insoluble materials by extraction with a volatile liquid hydrocarbon such as a petroleum naphtha. Aqueous detergent solutions are capable of holding on the order of 6% to 10% or more of such volatile liquid hydrocarbons in a state of pseudo or colloidal solution.

For economical operation, it is usually desirable to recover the volatile liquid hydrocarbons. Further, their separation from the aqueous detergent solutions is also desirable for other reasons. The presence of volatile liquid hydrocarbons in aqueous solutions of the detergents is objectionable because of their adverse effect upon the detergent, emulsifying and wetting ability of the solutions, and because of the fire hazard associated with their inflammability. When present in aqueous solutions of detergents which are to be converted to the solid form, they constitute a fire and explosion hazard; for example, they form explosive mixtures when the solutions are spray-dried in hot air or when the solutions are drum-dried in contact with air. Hence it is desirable, prior to the final drying operation, to reduce the amount of such hydrocarbons contained in aqueous detergent solutions of the type under consideration to 0.5% or less by weight.

If the volatile liquid hydrocarbons are removed from aqueous detergent solutions by batchwise distillation, the process at first proceeds satisfactorily. After the hydrocarbons are partially depleted, however, the quantity of foam increases and by its abundance hinders further conduct of the process which must then be completed slowly and carefully to avoid carrying foam along with vapor and causing a loss of detergent in the distillate. Since the distillation must be effected slowly, the distillation capacity of apparatus of given size is relatively low compared with its capacity for ordinary distillations. Consequently the removal of the hydrocarbons

from such detergents in this manner involves a relatively high capital cost for equipment.

The present invention has for its object improvements in the removal of volatile liquid hydrocarbon constituents from aqueous detergent solutions and is particularly concerned with a distillation process which minimizes foam formation and thereby reduces the cost of equipment necessary for distilling the hydrocarbons from the detergent solution.

The process of the present invention is particularly applicable to the treatment of aqueous detergent solutions of the type produced by the process of my application Serial No. 427,321, filed January 19, 1942. In accordance with the process of that application organic nitrosation-sulfitation products, such as the products of United States Patent 2,265,993, are subjected to an extraction with a volatile liquid hydrocarbon such as hexane, heptane, octane, hexene, heptene, octene, or mixtures of such hydrocarbons, in the presence of an emulsion breaker such as isopropyl alcohol. The aqueous detergents of the type thus extracted produce an abundance of foam and therefore present an especially difficult concentration problem.

In the ordinary distillation method, the hydrocarbons may be distilled satisfactorily along with water until the concentration of the hydrocarbons has been reduced to a point somewhat below 5%, since the foaming tendency is not so noticeable at higher concentrations (referred to herein as foam-breaking concentrations); but about at this point in the process the foaming increases rapidly until it becomes exceedingly difficult to continue the distillation without incurring substantial losses of aqueous detergent solution along with water and hydrocarbon vapor. The concentration of the hydrocarbons in the solution at the aforesaid point in the process is referred to herein as the minimum foam-breaking concentration.

The process of my invention provides a simple and effective solution of this difficulty.

In accordance with the process of the present invention, an aqueous solution of a detergent of good foaming qualities containing one or more volatile liquid hydrocarbons (that is, liquid hydrocarbons having normal boiling points below 150° C.), more particularly non-aromatic hydrocarbons (i. e., open-chain aliphatic and alicyclic hydrocarbons) having normal boiling points in

the range 50° to 150° C. is passed down through an evaporating column countercurrently to a flow of a hot inert gaseous evaporating medium such as steam, and at least a sufficient concentration of the said liquid hydrocarbon or hydrocarbons (i. e. at least the minimum foam-breaking concentration) is maintained, in liquid form, at the top of the liquid phase in the column (i. e. at the top of the countercurrent flow in the column) to substantially reduce the head of foam on the aqueous detergent.

In the practice of the present invention in accordance with a preferred method of procedure, the aqueous detergent solution containing one or more liquid hydrocarbons having normal boiling points between 50° and 150° C. is introduced into a hydrocarbon stripping zone at or near the top thereof, and an aqueous detergent solution from which the liquid hydrocarbon has been removed is withdrawn from a point near the bottom of this zone; steam is passed upwardly through the zone to evaporate the liquid hydrocarbon from the aqueous solution; and a high concentration of the liquid hydrocarbon, at least 5% by weight, is maintained at the upper surface of the zone to accelerate the breaking of foam. By maintaining the concentration of said liquid hydrocarbon in the aqueous detergent solution at the upper surface of the solution in the evaporating zone at 5% or more, the head of foam present may be dwarfed to a fifth or a tenth of the height which it may attain in the absence of this quantity of liquid hydrocarbon and a detergent solution may be produced containing less than 0.3% of hydrocarbon. The high concentration of liquid hydrocarbon in the solution at the top of the evaporator may be maintained by introducing the detergent solution containing a higher content of such liquid hydrocarbon and coordinating the supply of gaseous evaporating medium and the supply of aqueous detergent solution so as to avoid depletion of the hydrocarbon content at the upper surface.

The nature of my invention will be more fully appreciated from the following description of a specific embodiment thereof, which has been illustrated diagrammatically in the accompanying drawing.

In the drawing the numeral 1 designates a tower which is relatively tall compared with its cross-section and is insulated by heat insulation 2. This tower is partly filled with pervious packing material 3 such as crushed fire-brick, ceramic rings, or the like supported on a supporting grid 4. The essential purpose served by the packing is to inhibit vertical mixing and thus prevent liquid near the bottom, from which hydrocarbon has been removed, from returning to a higher point in the apparatus and thus diluting the hydrocarbon-rich liquid at the top and, conversely, increasing the hydrocarbon content in the lower regions of the evaporating zone. In place of a packed tower construction a series of plates or flooded bubble trays may be used.

The tower 1 has an inlet 5 near the top thereof for aqueous detergent solution containing the liquid hydrocarbon, and an outlet 6 at the bottom for withdrawal of aqueous detergent solution from which hydrocarbon has been removed. An inlet 7 is provided near the bottom of the tower for supplying steam. Preferably the steam is distributed by a distributor 8 within the tower. An outlet 9 is provided near the top of the tower for withdrawal of vapor products. A thermostat 10 a few feet below the foam-breaking level 11 may be provided.

to control the flow of steam by means of a valve 12 on steam line 1.

In the preferred operation of this system an aqueous detergent solution which may have the following composition by weight:

	Parts
Water	65
Skellysolve-C, a petroleum naphtha cut corresponding to heptane	8
Isopropyl alcohol	2
Surface-active organic sulfitation product consisting essentially of sulfonated ketones, sulfonated amines, sulfonated sulfamates, and water-soluble inorganic salts, such as can be obtained by the process of United States Patent 2,265,993	25

is introduced at an elevated temperature, preferably 60° to 70° C., through inlet 5. Steam (ordinary saturated steam under about 50 lb. gage pressure at 145-150° C.) is introduced at 7 and allowed to percolate up through the aqueous solution in the packing 3. The steam in passing up through the solution picks up vapors of the petroleum naphtha and isopropyl alcohol and carries them upwardly through the column in contact with aqueous detergent solution containing a gradually increasing proportion of them. Vapors of the petroleum naphtha, isopropyl alcohol, and steam are withdrawn through outlet 9; aqueous detergent is withdrawn at 6. The flow of detergent in at 5 and out at 6 is regulated to provide the desired degree of removal of petroleum naphtha and isopropyl alcohol, and at the same time to maintain the desired high concentration of petroleum naphtha at the foam-breaking level, designated 11 in the drawing. If the maximum available flow of detergent is inadequate to maintain a concentration of petroleum naphtha at 11 corresponding to at least 5% by weight of the aqueous detergent solution, the proportion of steam introduced at 7 may be reduced until the desired balance is obtained.

In towers from 6 to 20 feet in height, the process of my invention is capable of reducing the hydrocarbon and alcohol content of an aqueous detergent of the type described above to a small fraction of a percent, for instance on the order of 0.1%, and practically 100% removal of the hydrocarbon has been effected.

It will be realized by those skilled in the art that the invention is not limited to the details of the foregoing description and that changes can be made without departing from the scope of the invention.

The details of operation of my process naturally vary, depending upon the composition of the detergent solution and the identity of the volatile liquid hydrocarbon to be removed. Thus, if it is a heptane fraction, a vapor temperature of about 80° C. at the top of the column gives very good results with the above-described detergent solution. A higher boiling liquid hydrocarbon will usually require a higher temperature. Thus with a corresponding proportion of an octane fraction to be removed a ten degree higher temperature is more suitable. With either hydrocarbon, the liquid temperature at the bottom of the column is advantageously around 103° C. for the specific detergent composition described.

For the treatment of detergent solutions initially containing less than 5% by weight of hydrocarbon, the apparatus may be modified slightly by shortening the packed section below the inlet for detergent solution and providing an addi-

tional packed section above this inlet. A quantity of hydrocarbon of the type above referred to may then be added as a liquid at a point above the upper packed section to maintain the desired high concentration of the hydrocarbon at the top of the evaporating zone.

Detergent solutions having an inadequate concentration of hydrocarbon to assure satisfactory foam-breaking also may be treated in the type of apparatus illustrated in the drawing merely by adding the requisite quantity of volatile liquid hydrocarbon, in the liquid form, to the solution or to the tower to provide a suitable high concentration at the foam-breaking level. This procedure has the disadvantage, as compared with the provision of a second section above the detergent inlet, of requiring a somewhat larger quantity of hydrocarbon to maintain the same concentration thereof at the foam-breaking level.

If desired, heat in addition to that supplied by the steam may be provided through the tower walls from an external source or by heating coils within the tower. By supplying additional heat, particularly in a region extending for a few feet below the foam-breaking level, the capacity of a tower of given cross-sectional area can be increased considerably.

In normal operation, as above described, the tower pressure is atmospheric at the top and only slightly greater at the base, the level of the liquid overflow 12 being near the base of the tower. If desired, a greater hydrostatic pressure at the base of the tower may be employed, for example, by raising the level of the liquid overflow 12.

The separating process of the present invention may be controlled automatically in a very simple manner merely by providing a thermostatic control for the flow of steam while maintaining the detergent flow substantially constant. Thus, with the conditions of temperature prevailing in the case of the detergent previously considered, containing on the order of 8% of heptane, a thermostat may be provided in the tower 1 at an intermediate point (for instance in a 12 foot column, at a point three or four feet below the foam-breaking level) to maintain a substantially constant temperature of say 85° to 90° C. at this point by suitable control of the steam flow.

In a similar manner, other aqueous detergent solutions which tend to foam and which contain hydrocarbons of the type above described may be treated; for example, the various aqueous solutions obtained by the process of my application Serial No. 427,321, filed January 19, 1942, and especially those containing, per 100 parts by weight of solution, 6 to 10 parts of hydrocarbon, 25 to 40 parts of solids, and the balance water, the composition of the solids being: 40 to 55% of a mixture of surface-active organic sulfitation products consisting essentially of sulfonated ketones, sulfonated amines and sulfonated sulfamates, 15 to 25% of sodium sulfate, 10 to 14% of sodium chloride, 10 to 20% of sodium sulfite, 6 to 10% of sodium bisulfite, 1 to 3% of sodium sulfamate.

I claim:

1. The method of removing a liquid hydrocarbon having a normal boiling point below 150° C., contained in an aqueous detergent solution tending to foam when the concentration of said liquid hydrocarbon in said solution is less than the minimum foam-breaking concentration of said hydrocarbon in said solution, which comprises passing said solution down through an evaporating column countercurrently to a flow of hot inert gaseous evaporating medium, including in the solution near the top of the countercurrent flow in the column a concentration of said hydrocarbon at least equal to said minimum foam-breaking concentration, and controlling the rate of flow of the gaseous evaporating medium so as to maintain in the solution at the top of the countercurrent flow in the column, a concentration of said hydrocarbon at least equal to said minimum foam-breaking concentration.
2. The method of removing a liquid hydrocarbon having a normal boiling point below 150° C., contained in an aqueous detergent solution tending to foam when the concentration of said liquid hydrocarbon in said solution is less than the minimum foam-breaking concentration of said hydrocarbon in said solution, which comprises passing said solution down through an evaporating column countercurrently to a flow of steam, including in the solution near the top of the countercurrent flow in the column a concentration of said hydrocarbon at least equal to said minimum foam-breaking concentration, and controlling the rate of flow of the steam so as to maintain, in the solution at the top of the countercurrent flow in the column, a concentration of said hydrocarbon at least equal to said minimum foam-breaking concentration.
3. The method of removing a liquid hydrocarbon having a normal boiling point in the range 50° to 150° C., contained in an aqueous detergent solution tending to foam, which comprises passing the solution down through an evaporating column containing the solution as the continuous phase, bubbling steam countercurrently up through the solution, and maintaining in the solution near the top of the column an amount of the liquid hydrocarbon equal to at least 5% by weight of the liquid phase.
4. The method of removing a volatile non-aromatic hydrocarbon having a normal boiling point in the range 50° C to 150° C., contained in an aqueous detergent solution tending to foam, which comprises passing the solution down through an evaporating column containing the detergent solution as the continuous phase, bubbling steam countercurrently up through the solution, introducing near the top of the column hot, aqueous detergent solution containing the volatile non-aromatic hydrocarbon at a rate sufficient to maintain in the liquid at the foam-breaking level in the column a concentration of said hydrocarbon at least 5% by weight of the liquid phase, and withdrawing substantially hydrocarbon-free aqueous detergent solution from the base of the column.
5. The method of removing a hydrocarbon having a normal boiling point in the range 50° to 150° C., contained in an aqueous solution of a surface-active organic sulfitation product consisting essentially of sulfonated ketones, sulfonated amines, sulfonated sulfamates, and water-soluble inorganic salts, said solution tending to foam when the concentration of said hydrocarbon in said solution is less than the minimum foam-breaking concentration of said hydrocarbon in said solution, which comprises passing aqueous solution containing said hydrocarbon down through an evaporating column countercurrently to a flow of steam, including in the solution near the top of the countercurrent flow in the column a concentration of said hydrocarbon at least equal to said minimum foam-breaking concentration, and controlling the rate of flow of the steam

- so as to maintain, in the solution at the top of the countercurrent flow in the column, a concentration of said hydrocarbon at least equal to said minimum foam-breaking concentration.
6. The method of removing a volatile non-aromatic hydrocarbon having a normal boiling point in the range 50° to 150° C., contained in an aqueous solution of a surface-active organic sulfitation product consisting essentially of sulfonated ketones, sulfonated amines, sulfonated sulfamates, and water-soluble inorganic salts, said solution tending to foam when the concentration of said hydrocarbon in said solution is less than the minimum foam-breaking concentration of said hydrocarbon in said solution, which comprises passing said aqueous solution containing said hydrocarbon down through an evaporating column countercurrently to a flow of steam, including in the solution near the top of the countercurrent flow in the column a concentration of said hydrocarbon at least equal to said minimum foam-breaking concentration, and controlling the rate of flow of the steam so as to maintain, in the solution at the top of the countercurrent flow in the column, a concentration of said hydrocarbon at least equal to said minimum foam-breaking concentration.
7. The method of removing a petroleum naphtha contained in an aqueous solution of a surface-active organic sulfitation product consisting essentially of sulfonated ketones, sulfonated amines, sulfonated sulfamates, and water-soluble inorganic salts, which comprises passing the aqueous solution containing a petroleum naphtha down through an evaporating column, bubbling steam countercurrently up through the solution, and maintaining in the solution at the foam-breaking level in the column an amount of the petroleum naphtha equal to at least 5% by weight of the solution.
8. The method of removing a volatile non-aromatic hydrocarbon having a normal boiling point in the range 50° to 150° C., contained in an aqueous solution of a surface-active organic sulfitation product consisting essentially of sulfonated ketones, sulfonated amines, sulfonated sulfamates, and water-soluble inorganic salts, which comprises passing the solution continuously down through an evaporating column containing the aqueous solution as the continuous phase, bubbling steam countercurrently up through the solution so as to evaporate the hydrocarbon from the aqueous solution, introducing additional quantities of the aqueous solution containing the hydrocarbon at a temperature of at least 60° C., withdrawing substantially hydrocarbon-free solution substantially continuously from the base of the column, and controlling the introduction of steam at the base of the column so as to provide a substantially constant temperature at an intermediate point of the column preselected to maintain in the liquid at the foam-breaking level in the column a concentration of the hydrocarbon at least 5% by weight of the liquid phase and an effluent detergent solution at the base of the column substantially free from hydrocarbon.
9. The method of removing a petroleum naphtha contained in an aqueous solution of a surface-active organic sulfitation product consisting essentially of sulfonated ketones, sulfonated amines, sulfonated sulfamates, and water-soluble inorganic salts, which comprises passing the solution continuously down through an evaporating column containing the aqueous solution as the continuous phase, bubbling steam countercurrently up through the solution so as to evaporate the petroleum naphtha from the aqueous solution, introducing additional quantities of the aqueous solution containing the petroleum naphtha at a temperature of at least 60° C., withdrawing substantially naphtha-free solution substantially continuously from the base of the column, and controlling the introduction of steam at the base of the column so as to provide a substantially constant temperature at an intermediate point of the column preselected to maintain in the liquid at the foam-breaking level in the column a concentration of the petroleum naphtha at least 5% by weight of the liquid phase and an effluent detergent solution at the base of the column substantially free from petroleum naphtha.
10. The method of removing a liquid hydrocarbon having a normal boiling point below 150° C., contained in an aqueous detergent solution tending to foam when the concentration of said hydrocarbon in said solution is less than the minimum foam-breaking concentration of said hydrocarbon in said solution, which comprises passing the solution, containing at least said minimum foam-breaking concentration of said hydrocarbon, down through an evaporating column countercurrently to a flow of a hot inert gaseous evaporating medium, and coordinating the rate of flow of said evaporating medium with the rate of downward flow of said solution so as to maintain at least said minimum foam-breaking concentration of the hydrocarbon in the solution near the top of the column.
11. The method of removing a liquid hydrocarbon having a normal boiling point below 150° C., contained in an aqueous detergent solution tending to foam when the concentration of said hydrocarbon in said solution is less than the minimum foam-breaking concentration of said hydrocarbon in said solution, which comprises passing the solution, containing at least said minimum foam-breaking concentration of said hydrocarbon, down through an evaporating column countercurrently to a flow of steam, and coordinating the rate of flow of the steam with the rate of downward flow of said solution so as to maintain a substantially constant temperature at a preselected intermediate point in the column, the temperature at said point being selected so as to maintain at least said minimum foam-breaking concentration of said hydrocarbon in the solution near the top of the column.
12. The method of removing a liquid hydrocarbon having a boiling point below 150° C., contained in an aqueous detergent solution tending to foam when the concentration of said hydrocarbon in said solution is less than the minimum foam-breaking concentration of said hydrocarbon in said solution, which comprises passing the solution, containing at least said minimum foam-breaking concentration of said hydrocarbon, down through an evaporating column countercurrent to a flow of steam, and thermostatically controlling the rate of flow of the steam, relative to the rate of flow of said solution in the column, in accordance with the temperature at a preselected intermediate point in the column so as to maintain a substantially constant temperature at said point, said temperature being selected so as to maintain at least said minimum foam-breaking concentration of said hydrocarbon in the solution near the top of the column.

WILLIAM ALFRED FESSLER.
